UNITED STATES PATENT OFFICE.

CHARLES F. FREDE, OF ST. LOUIS, MISSOURI, ASSIGNOR TO COMMONWEALTH STEEL COMPANY, OF ST. LOUIS, MISSOURI, A CORPORATION OF NEW JERSEY.

METAL-PLANING MACHINE.

1,215,514.

Specification of Letters Patent. Patented Feb. 13, 1917.

Application filed April 13, 1914. Serial No. 831,518.

To all whom it may concern:

Be it known that I, CHARLES F. FREDE, a citizen of the United States, residing at St. Louis, in the State of Missouri, have invented a new and useful Improvement in Metal-Planing Machines, of which the following is a specification.

My invention relates to a metal planing machine, and has for its object to enable a metallic surface to be planed transversely from either side, or from both sides simultaneously, of the machine, in lieu of longitudinally as in the ordinary manner.

It consists in features of novelty as hereinafter described and claimed, reference being had to the accompanying drawing forming part of this specification, whereon,

Figure 1, is a front elevation of my improved cross cut metal planing machine with the electrically operated motors (omitting the wiring connected therewith) preferably used for driving the same; Fig. 2, a top plan thereof (broken away); Fig. 3, a side elevation of the same looking from the left; Fig. 4, a detached view to enlarged scale, of the center-rail (broken away), showing part of one of the cutter-heads and combined feed mechanism as seen to the left in Fig. 1; Fig. 5, a top plan of the same; Fig. 6, a vertical transverse section therethrough on line 6, 6, in Fig. 4; Fig. 7, a cross-section on line 7, 7, in Fig. 6; Fig. 8, a top plan of the center-rail corresponding to Fig. 2, showing a preferable system of wiring for electrically operating the drive motors of the machine, and Fig. 9, a diagrammatic view of the said wiring in which the terminals of the field and armature coils are represented by binding posts in Fig. 8.

Like letters and numerals of reference denote like parts in all the figures.

Referring to Figs. 1 to 7, *a* represents the bed, *b* the housing, *c* the center-rail, and *d* the platen of my improved cross cut metal planing machine, the center-rail *c* being fixed to the guide-blocks *e* and adjustable vertically therewith on the face of the housing *b* in the usual well-known manner (not shown).

In the face of the center-rail *c* for its entire length, is formed a recess *f* in which is arranged on one side of the longitudinal center of the machine, preferably, a right-handed screw-threaded shaft *g*, and on the other side a left-handed screw-threaded

shaft *g'*, the shafts *g*, *g'*, being mounted and independently rotatable in suitable end bearings *h* and a common middle bearing *h'* as shown.

On the outer end of the shaft *g* beyond the corresponding end of the center-rail *c* is fixed preferably, a spur wheel *i* which is engaged by a pinion *j* fixed on the shaft *h* of an electrically operated motor *l*; and on the outer end of the shaft *g'* is fixed a spur wheel *i'* which is engaged by a pinion *j'* fixed on the shaft *h'* of an electrically operated motor *l'*, the motors *l*, *l'*, being fixed on the center-rail *c* and adjustable there-with vertically on the housing *b*.

Immediately over the center-rail *c* longitudinally and parallel thereto, is arranged a bar *m* (see particularly Figs. 4 to 6) of suitable length and cross section (such as inverted L-shape as shown) which is adapted to slide longitudinally in guides *n* fixed to the center-rail *c*, and from the face of the bar *m* project two dogs *o* at a suitable distance apart, which are adjustable along a slot *p* formed longitudinally in the face of the bar *m* and held thereto, preferably in the present case, respectively, by a screw-threaded shank *q* (Figs. 4 and 5) projecting rearward from the dog *o* through the slot *p* and engaged by a hand-nut *q'* for clamping the dog *o* to the bar *m* and releasing it therefrom as required. *r*, *r'* are the cutter-heads (one on each side of the longitudinal center of the machine) which with the cutters *s*, *s'*, are carried by, and adapted to slide along the face of the center-rail *c*, the right-handed screw-threaded shaft *g* passing through and engaging in a correspondingly threaded lug *t* (shown by dotted lines in Figs. 1 and 3) projecting from the rear side of the body portion of the cutter-head *r*, whereby on the rotation of the shaft *g* in either direction, the cutter-head *r* with its cutter *s* is moved to or from the longitudinal center of the machine as the case may be. Similarly, the left-handed screw-threaded shaft *g'* passes through and engages in a lug *t'* projecting from the cutter-head *r'* for moving the latter with its cutter *s'*, as in the case of the cutter-head *r*.

From the rear side of the cutter-head *r*, preferably at the top, projects a lug *u* which is adapted to engage the dogs *o* of the bar *m* as hereinafter more particularly described, and from the rear side of the cut-

ter-head r' projects a similar lug u' for engaging the dogs o' (shown by dotted lines to the right in Fig. 2) when the cutter-head r' only, is used and the cutter-head r idle, in which case the dogs o are preferably, moved along the slot p away from the lug u of the cutter-head r . The dogs o' project from the face of the bar m and are adjustable along a slot p' formed longitudinally in the face of the bar m to which they are held by the hand-nut g^2 in a similar manner to the dogs o before described.

On the platen d beneath the cutter-heads r, r' , is placed the casting v (or other metal object) to be planed transversely, preferably from both sides simultaneously, in lieu of longitudinally by the travel of the platen as in the ordinary manner, the longitudinal movement of the platen v in the present case being intermittent and limited to the extent of the feed thereby imparted to the cutters s, s' , at each stroke of the cutter-heads r, r' .

For advancing the platen d to the extent of the required feed as above mentioned, the bar m is formed transversely, preferably at the top adjacent to the cutter-head r , with a series of teeth w which are engaged by a spur wheel w' freely revoluble on a horizontal spindle x which is mounted in a bearing y fixed to the center-rail c , and on the spindle x between the wheel w' and the bearing y is a ratchet wheel z which is fixed to the spindle x preferably by a set screw z' , and engaged by a ratchet pawl 1 fixed at one end to the rear side of the wheel w' and adapted at its other end to engage with the teeth of the ratchet wheel z , so that on rotation of the wheel w' to the right (as indicated by the full curved arrow in Figs. 1 and 4) by the teeth w of the bar m when the latter is moved longitudinally to the right (as indicated by the horizontal arrow in Figs. 1, 4, and 5, and hereinafter more particularly referred to), the spindle x will be rotated to the right correspondingly to the wheels w' and z , and thereby similarly rotate preferably, a bevel wheel 2 fixed on the rear end of the spindle x , and adapted to engage in a bevel wheel 3 which is fixed on a horizontal spindle 4 mounted at right angles to the spindle x in suitable bearings 5 fixed to and carried by the center-rail c , the spindle 4 projecting through an opening 6 (Fig. 3) in the side of the housing b and having fixed thereto at its outer end a bevel wheel 7 which is adapted to engage in a bevel wheel 8 adjustably fixed on an upright shaft 9 for maintaining its engagement with the bevel wheel 7 in whatever position the center-rail c with its appendages as described may be in the vertical adjustment of the guide-blocks e along the housing b .

On the upright shaft 9 which is mounted in suitable bearings $10, 11$, fixed to the hous-

ing b , is fixed a bevel wheel 12 which is adapted to engage in a bevel wheel 13 fixed on a horizontal shaft 14 which extends below the level of the platen d to the front end of the bed a and is mounted in suitable bearings 15 and $15'$ fixed respectively to the housing b and bed a . On the shaft 14 at its front end is fixed a bevel wheel 16 which is adapted to engage in a bevel wheel 17 fixed to the outer end of a horizontal shaft 18 which is mounted at right angles to the shaft 14 in suitable bearings 19 fixed to the bed a the other end of the shaft 18 having a bevel wheel 20 adapted to engage in a bevel wheel 21 fixed to the outer end of a screw-threaded shaft 22 which extends horizontally the entire length of the bed a beneath the platen d at its longitudinal center, the shaft 22 being mounted in bearings 23 formed, one at each end of the bed a , and passing through and engaging in a correspondingly screw-threaded lug or bracket 24 which projects from the underside of the platen d , whereby on the intermittent rotation of the feed gears as above described, the shaft 22 is correspondingly partially rotated and the platen d advanced accordingly.

On the rotation of the spur wheel w' of the feed gear to the left (as indicated by the curved dotted arrow in Fig. 4), by the teeth w of the bar m when the latter is moved longitudinally to the right (as indicated by the horizontal dotted arrow in Figs. 1, 4, and 5), the ratchet pawl 1 will ride over or out of engagement with the ratchet wheel z and the spindle x be consequently idle or stationary.

In the mechanical operation of the machine as above arranged, without reference to the means (hereinafter particularly described) for electrically operating the motors l, l' , but assuming them to be in operation with their shafts k, k' , and pinions j, j' , and the spur wheels i, i' , with their right and left hand screw shafts g, g' , rotating respectively in the directions indicated by the arrows seen in Figs. 1, 2, and 3, and assuming the cutter-heads r, r' , with their cutters s, s' , to be in the position shown by full lines in Fig. 1, or with the cutters s, s' , on the outward or return stroke of the cutter-heads r, r' , just clear of the side of the casting v , on the continuation of the said stroke the lug u on the cutter-head r , engaging the left hand dog o of the bar m , will force the latter in the corresponding direction (as indicated by the full arrows) and in so doing, its teeth w partially rotating the spur wheel w' to the right will thereby cause the feed gears as hereinbefore fully set forth, to advance the platen d with the casting v to an extent corresponding to the required feed of the cutters s, s' , until, on the completion of the said stroke of the cutter-head r , the bar m and dogs o

are moved into the dotted position seen in Figs. 4 and 5, when on reversal of the motors l , l' , the cutter-heads r , r' , with their cutters s , s' , will be moved simultaneously by the screw shafts g , g' , inward across the casting v , or in the direction of the dotted arrows, toward the longitudinal center of the machine, and in so doing the lug u on the cutter-head r will engage the other or right hand dog o and force it with the bar m from the dotted position seen in Figs. 4, and 5, to its normal position as seen in full lines Figs. 1, 2, 4, and 5, whereby the teeth w of the bar m will rotate the spur wheel w' in the opposite direction (as indicated by the curved dotted arrow in Fig. 4), or so that the ratchet pawl 1 will ride over and out of engagement with the ratchet wheel z and the feed gears thereby remain stationary.

It is to be here noted that, when the cutter-heads r , r' , with their cutters s , s' , are operated simultaneously as described, the dogs o' are not in use, but are moved along the slot p' away from and out of engagement with the lug u' on the cutter-head r' . On the other hand when it is desired to use the cutter-head r' with its cutter s' for planing the casting v from the corresponding side only, the dogs o' are adjusted for engagement by the lugs u' , and the dogs o preferably, moved out of engagement with the lugs u on the cutter-head r which remains idle, the bar m in this case being moved by the dogs o' so as to feed when the cutter s' is clear of the casting v and nearing the end of its inner or cutting stroke.

For automatically controlling the electric operation of the motors l , l' , (Figs. 8 and 9) an arm 25 fixed to and projecting rearwardly from the bar m is coupled at its free end to the corresponding end of the knife blade switch lever 26 which is hinged at its other end to a bracket 27 carried by and insulated from the center-rail c , the bracket 27 being connected with the electric feed wire 28 and return wire 28' from and to the dynamo (not shown), or other source of electric supply, respectively, and the switch lever 26, as shown by full lines, in engagement with contacts 29, 30, 31, 32, whereby the electric current passes through contact 29 and its wires, through the field coil 33, returning to generator through contact 31, the current also passing through contact 29 and its wires, through the intermediate switch 34, and field coil 33', returning to generator through intermediate switch 34 and contact 31; also the current passes through contact 30 and its wires, through armature 35, returning to generator through contact 32, also through contact 30 and its wires, and intermediate switch 34', through armature 35', returning to generator

through intermediate switch 34' and contact 32, whereby the motors l , l' , operate to drive the cutter-heads r , r' , in the return direction, and in so doing the bar m is moved in the direction of the full arrow seen in Figs. 1 and 5 and causes the arm 25 to throw the switch lever 26 out of engagement with the contacts 29, 30, 31, 32, and into engagement with contacts 36, 37, 38, 39, which causes the current to pass through contact 36 and its wires, field coil 33, and through intermediate switch 34, through field coil 33', returning to generator through contact 38, the current also passes through contact 37 and its wires, through armature 35, and through intermediate switch 34', and armature 35', returning to generator through contact 39, and as the current in this case passes through the armatures 35, 35', in opposite directions to that when contacts 29, 30, 31, 32, are engaged, the motors l , l' , will be driven in the reverse direction and the cutter-heads r , r' , driven in the contrary direction accordingly.

By disconnecting the arm 25 from the switch lever 26 and connecting arm 25' (indicated by dotted lines in Figs. 2 and 8) to switch lever 26', and at the same time using dogs o' in lieu of dogs o , the electrical operation of the machine may be controlled by the cutter head r' , the current flowing through contacts 29, 30, 31, 32, for operating the return stroke, and through contacts 36', 37', 38', 39', for operating the cutting stroke, the current passing from and returning to the generator through wires 28², and 28³, respectively.

Either cutter-head r , r' , may be operated independently by opening the intermediate switches 34, 34', and connecting either of the arms 25, 25', respectively to the switch levers 26, 26', and at the same time using dogs o , or o' as required.

If either cutter-head r or r' is in action alone and it is desired to operate them simultaneously, the intermediate switches 34 and 34' may be closed at any point of the cutting or return stroke of the operating cutter-head, with the idle cutter-head in any position of its travel.

To this end it will be noted that, the travel of the cutter-heads r and r' is limited in each direction by the bearings h and h' respectively, of the right and left handed screw-threaded shafts g and g' (or by any other equivalent means that may be provided for the purpose). If the cutter-head r is operating, and is in the position shown in Fig. 5, having nearly completed its return stroke, the cutter-head r' being in the position shown in Fig. 1, having just completed its return stroke, and all the switches in the position on the drawing, except that the intermediate switches 34 and 34' are assumed to be open, and it is desired to operate the

cutter-heads r and r' simultaneously, it is only necessary to close the intermediate switches 34 and 34' when electric current will be directed through the proper connections and through the motor l' so as to cause the latter to rotate in a direction to move the cutter-head r' outward or on its return stroke, but as the cutter-head r' has already completed its return stroke, its further movement in this direction is stopped by the end bearing h (or its equivalent device). In the meantime the cutter-head r will continue its return stroke and upon reversal of the electric current through switch lever 26, current will be directed through the proper wires to cause both the motors l, l' to rotate in a reverse direction or so as to drive the cutter-heads r and r' in a cutting stroke direction. A similar action will take place no matter in what position the idle cutter-head may have stopped. It is here noted that, in operating the cutter-heads r, r' ; simultaneously they move in opposite directions to each other at all times, for effecting which the controlling means are so arranged that, the cutter-heads

r, r' , cannot be operated simultaneously independent of each other.

I claim,

In a metal planing machine, the combination with the bed and the platen having a suitable housing, of a center-rail arranged above and across the platen and vertically adjustable on the housing, a cutter-head slideable along the center-rail on each side of the longitudinal center of the machine and adapted to cut transversely to the platen, motors carried by the center-rail and adapted to reciprocate the cutter-heads respectively, along the center-rail, means for electrically controlling the said motors, so that, either of the said cutter-heads may be stopped and started independent of the other, and that, when one cutter-head only is in action and the other is started, the said cutter-heads will automatically operate in opposite directions.

CHARLES F. FREDE.
